AUTOMATIC MAGAZINE SLIDE PROJECTOR

Theodore S. Briskin, Chicago, Robert L. Moore, La Grange Highlands, and Rudolph A. Rom, Stickney, Ill., assignors, by mesne assignments, to Revere Camera Company (formerly Samica Corporation), a corporation of Delaware

Filed Mar. 21, 1955, Ser. No. 495,474

13 Claims. (Cl. 88—28)

This invention relates to slide projectors and, in particular, to projectors for successively projecting a number of slides onto a screen.

The particular embodiment of the invention shown herein is an automatic slide projector in which the slides are arranged in a single magazine from which the slides may be successively displaced into projecting position and to which magazine each slide is returned after projection. However, certain aspects of the invention are equally applicable to non-automatic slide projectors.

The particular embodiment shown in one respect is an improvement of the automatic projector shown in the application of Conrad J. Peto, Serial No. 146,655, filed February 28, 1950, now Patent No. 2,705,438, dated April 5, 1955. In other words, the projector embodies mechanism which is caused to operate in a cycle of operation which commences and terminates at a time when a slide is in projecting position. Thus, the interval between successive cycles, which interval can be controlled by the operator, is the time during which the slide is projected onto the screen. Such mechanism also embodies means for stopping the mechanism midway of the cycle of operation at the time when the slide has been returned to the magazine and prior to the displacement of the next succeeding slide therefrom. Thus, the magazine may be removed from the projector at a time when all of the slides are contained therein.

One object of the present invention is to provide in a projector of the type above outlined, an improved mode of operation, characterized by the terms "semi-automatic," in which the interval between successive cycles is controlled by the operator, "fully automatic" in which the interval between successive cycles is automatically controlled, and "manual" in which the mechanism operates through only successive portions of a complete cycle, and in which the timing of said successive portions is under manual control.

Another object of the present invention is to provide improved cycling means to control the operation of the projector mechanism, which cycling means is adapted to operate according to any one of the three modes of operation outlined above.

Still another object is to provide a projector embodying pulse actuated control means whereby the projector can be electrically connected to a tape recorder or other external programming means to the end that the operation of the projector may be synchronized with the operation of said external device.

Still another object is to provide a slide projector having improved slide displacing or transporting means, and in particular, one in which the motion of the slide displacing elements is essentially rotational, as contrasted with translational, thereby providing a more compact and commercially acceptable mechanism.

In this connection, a generally arcuate path is provided for the slide, but the rotating elements are so designed as to have a radius much less than the radius of the arcuate path, thus reducing the compactness of the mechanism

2

to a greater extent than would result by the substitution of rotating elements for translating elements.

A still further object is to provide a magazine type of slide projector in which the magazine is oriented with respect to the projecting mechanism in such a manner that the slides, due to gravity, are automatically arranged in proper position for proper cooperation with other elements of the mechanism.

Still another object of the present invention is to provide a magazine type of projector embodying improved means for advancing the magazine.

Other objects are to provide, in a slide projector, an improved shutter, together with automatic means for operating the same, a novel and improved built in pointer, and improved magazine construction, and an improved lamp mounting means.

Other objects, features and advantages will become apparent as the description proceeds.

With reference now to the drawings in which like reference numerals designate like parts:

Fig. 37 is an enlarged detailed vertical section taken along line 37-37 of Fig. 36;

Fig. 38 is an end view of Fig. 36;

Fig. 39 is a detailed view showing one of the shutter blades;

Fig. 40 is a plan view of the slot and pointer plate sub-assembly, corresponding generally to the plan section of Fig. 23;

Fig. 41 is a front elevation thereof;

Fig. 42 is a rear elevation of one of the plate elements;

Fig. 43 is an end view of Fig. 42; and

Fig. 44 is an electrical diagram illustrating the relationship of certain of the parts.

The mechanism of the projector shown is mounted in, and partially enclosed by, a box-shaped casing 50, as shown in Figs. 4 and 8. Suitably secured to the upper edges of the casing 50 is a closure member 51 which is in the form of a die casting which encloses the upper part of the mechanism. This closure member comprises a lamp chamber portion 52 at the left rear, a lens receiving portion 53 at the left front, and a tunnel portion 54 at the right. The terms "left" and "right" as used herein refer to left and right as viewed from the front, as in Fig. 1, and the term "longitudinal" indicates the direction parallel to the axis of the optical system.

A lens unit 55 is telescopically received within the lens receiving portion 53. A slide magazine 56 is received within the tunnel portion 54. A lamp 58, shown in Figs. 3 and 4, is suitably mounted in the lamp chamber portion 52, and a suitable cover 57 is disposed over this portion 52 as a light shield. The space between the cover 57 and the upper edge of the lamp chamber portion 52 forms a slot serving as the intake for the air stream customarily used for cooling the lamp and lamp chamber. Grills 59, located at the front and side portions of the casing 50 serve as air outlets, and the air is caused to circulate by means of a blower 92 hereinafter described. As shown in dotted lines in Figs. 4 and 8, a removable cover 60 may be provided which cooperates with the casing 50 to completely enclose the projector when the same is not in use.

The casing 50 is provided with rear feet 61 and an adjustable front foot 62. A suitable control member 63 for the adjustable front foot 62 projects through the front surface into closure member 51, so that the angle of projection can be conveniently regulated. Similar adjusting means can be provided for one of the rear feet 61 to regulate the tilt.

Various operating elements project through the closure member 51, as follows: a focusing knob 64 for the lens unit 55, a release button 65, a function knob 66, a slide selector knob 67, a switch knob 68 for the motor and lamp, a pointer knob 69, and a shutter control lever 70, all as shown in Figs. 1 to 3. A slot 71 is also formed in the left side by means of which a slide, such as one ele-

ment of a stereo slide may be manually inserted into the light path.

The optical system, as shown in Fig. 4, comprises a mirror 72, condenser lenses 73, and projection lenses 74.

The complete mechanism assembly, which is enclosed within elements 50 and 51, is shown in Figs. 5, 6, and 22. The framework comprises a vertical transverse plate 80, a horizontally extending bridge member 81 secured thereto, and various other structural members, only some of which need be specifically mentioned. Most of these structural members may be formed from sheet steel, and secured to each other by rivets or welds.

As shown in Fig. 4, a vertical transverse closure plate 82 is secured to the bridge member 81 and cooperates with elements 80 and 81 to form an enclosure 85 in which certain of the mechanism is located. In other words, comparing Figs. 6 and 8, the various cams, links and levers, shown in Fig. 8, are located behind the closure plate 82, shown in Fig. 6. Disposed within the enclosure 85 is an intermediate vertical plate 83, as shown in Fig. 4. A bottom plate 86, shown in Figs. 4, 5, and 8 is also provided for the enclosure 85, and a motor support 87 is provided forwardly and somewhat above the bottom plate 86.

The mechanism assembly is suitably secured to the elements 50 and 51 at various places, such as the flange 84 at the bottom of the vertical plate 80.

The drive means

The mechanism is driven by means of a motor 90, shown in Figs. 4, 5 and 6, which is mounted on the motor support 87. A blower 92 is mounted at the lower end of the motor shaft 91 so as to be directly driven thereby. Suitably journaled in bridge member 81 and the bottom plate 86 are a clutch assembly 93 and a vertical shaft 94, the latter being provided with a worm 95. A pulley 96 forms a part of the clutch assembly 93, and it is driven from the motor shaft 91 by means of a belt 97. Suitable gearing 98, shown in Fig. 5, causes the vertical shaft 94 to be driven from the pulley. According to this arrangement, the blower, the pulley 93, the vertical shaft 94 and the worm 95 are directly and continuously driven from the motor 90.

The details of the clutch assembly 93 are shown in Figs. 5 and 8. A hollow bushing 100 is mounted in the bridge plate 81 and a thrust bushing 101 is mounted in the bottom plate 86. A bored shaft 102 has a reduced end portion 103 which is received in the thrust bushing 101. A worm 104, which includes a sleeve portion, is suitably secured to the bored shaft 102 so as to rotate therewith, and the sleeve portion surrounds a reduced portion of the bushing 100 to provide a bearing for the upper end of the bored shaft 102.

The pulley 96 is rotatably mounted on the reduced end portion 103 of the bored shaft 102, the pulley hub also including the first element of the gearing 98.

Clutch means are provided to provide a driving connection between the pulley 96 and the bored shaft 102. This clutch means includes a drive member 105 resiliently carried on the pulley 96, the drive member being provided with a suitable friction facing. A cooperating driven member 106 is slidably mounted on the bored shaft 102, and is caused to rotate with the shaft by means of a suitable pin 108 which passes through the driven member and through a slot 107 formed in the bored shaft 102. The driven member 106 is also provided with a friction facing. A light spring may be located within the bore of the bored shaft 102 which engages the pin 107 to urge the driven member 106 upwardly into disengaged position.

A rod 109 is received within the bored shaft 102 and bears downwardly against the pin 108 to cause operation of the clutch.

A horizontally extending tab 114 on the bridge member, provided with a suitable friction facing, engages the upper surface of the upwardly biased driven member 106 to serve as a brake when the clutch is disengaged. Thus, depression of rod 109 causes worm 104 to be driven from

the motor 90; when the pressure is relieved, the worm ceases its rotation.

A solenoid 110, mounted on bridge member 81, is provided for depressing the rod 109. As shown in Fig. 5, the solenoid 110 is provided with an armature 111 and a second rod 112 extends between the armature 111 and the first rod 109. The release button 65 is located immediately over the armature 111. Thus, when the release button 65 is depressed, the clutch will be engaged, causing rotation of the worm 104. As an alternative mode of operation, the solenoid 110 may be energized, thus causing engagement of the clutch. De-energization of the solenoid will cause disengagement of the clutch.

A microswitch 113 shown in Figs. 8-10, is suitably connected in series circuit with the solenoid 110 to control the operation thereof as above outlined; the mechanism for operating the microswitch will be more fully described hereinafter.

The slide transporting mechanism

The mechanism driven from the worm 104 can be located with respect to three horizontal shafts which are suitably mounted in the vertical plates 80 and 83. These three shafts, shown in Figs. 8-10, are the cam shaft 116, the follower shaft 117, and the rock shaft 118.

Secured to the cam shaft 116 so as to cause rotation thereof is a main gear 120, in the form of a worm wheel, which meshes with and is driven by the worm 104, as shown in Fig. 9. Projecting from the forward surface of the main gear 120 is a crank pin 121 to which is affixed one end of a link 122. The other end of the link is connected to a crank arm 123 which is secured to the rock shaft 118 so as to cause rotation thereof. Thus, continued unidirectional rotation of the main gear 120 will cause oscillation of the rock shaft 118, and as pointed out below, the parts are so proportioned that the amplitude of oscillation will be approximately 110°.

The rock shaft 118 extends rearwardly through and beyond the vertical plate 80 as shown in Fig. 11. Rearwardly of the plate 80, an injector arm 124 is mounted on the rock shaft 118 so as to rotate therewith, the manner of mounting being hereinafter described in greater detail. The injector arm is characterized by an arc-shaped portion 124a which is adapted to project through a suitable slot 277 formed in the magazine 56 so as to engage a slide held in the magazine and to displace the same into the projecting position shown in Fig. 9. To facilitate slide displacement, the end of the injector arm is provided with a concave edge 125 as shown in Fig. 14a.

Movement of the slide from the Fig. 9 position to the Fig. 10 retracted position is effected by an ejector arm 126 which is pivotally mounted on the rear surface of the vertical plate 80 by pivot means 127. The upper end of the ejector arm 126 is provided with a nylon disk 128 also having a concave edge for slide engagement. A link 129 connects the ejector 126 with the injector arm 124, as shown in Fig. 14, so that the two will move together, maintaining substantially uniform distance between a disk 128 and the concave edge 125, which distance may desirably be somewhat greater than the width of the slide so as to provide a small amount of lost motion.

The injector arm 124 is mounted on rock shaft 118 so as to move therewith; however, a lost motion connection is provided for the in feed, and a second lost motion connection is provided on the outfeed. The lost motion connection on the in feed is more in the nature of a safety overthrow which permits continued operation of the driving mechanism in the event that a slide should become jammed. The lost motion connection on the out feed is primarily for the purpose of providing a dwell in the operation of the injector arm, during which dwell the magazine advance takes place. In other words, as will be pointed out hereinafter, the magazine advance is timed for operation during the time that the injector arm 124 is in its retracted or Fig. 10 position. However, the out

feed lost motion is also operative in the case of a jammed slide during ejection, and to this extent it also provides a safety overthrow.

The lost motion mechanism is illustrated in Figs. 11, 11a, and 11b. The injector arm 124 is mounted on a hub in the form of a sleeve 130, the rear end of which terminates in a driven clutch dog 131, having a length of approximately 90°.

Disposed rearwardly of the sleeve 130 is a second sleeve 132, the forward end of which is provided with a driving dog 133 of about 180° length. The rear end of sleeve 132 is provided with a driven dog 134 of a length somewhat less than 180°. The rock shaft 118 is provided with a pin 135 which extends from only one side of the shaft, as shown in Fig. 11b.

The in feed lost motion, shown in Fig. 11a, is provided by dogs 131 and 133, and they provide a lost motion of about 90°. An overthrow spring 136, connected at either end to elements 130 and 132, biases the driven element 130-131, in the counterclockwise direction as viewed in Fig. 11a. In other words, on the in feed, the overthrow spring 136 provides the driving connection, but up to 90° of lost motion is permitted. Since, as shown by comparison of Figs. 9 and 10, the motion of the injector arm 124 is 60°, the in feed lost motion is sufficient to accommodate the entire motion of the injector arm.

The outfeed lost motion shown in Fig. 11b, is provided by the pin 135 and the dog 134. A second overthrow spring 137 extends between the pin 135 and the dog 133, and thus provides a driving connection between elements 118 and 132 during the outfeed. In other words, the elements 134 and 135 provide an out feed lost motion of substantially 180°. The oscillation of the rock shaft 118 is approximately 110°, of which approximately 60° is utilized in driving the injector arm 134, leaving 50° to be taken up by the two lost motion connections. The linkage 120-122-123 is such that 25° lost motion in the retracted or Fig. 10 position will occupy approximately 120°, thus allowing sufficient time for actuation of the magazine advance mechanism. A lost motion of from 15° to 25° in the projecting or Fig. 9 position, which represents upwards of 90° of motion of the main gear 120, is sufficient to accommodate the necessary de-clutching of the clutch assembly 93, and the subsequent clutching which are incident to either manual, semi-, or fully automatic operation, together with the operation of the cycling control mechanism to be hereinafter described.

Magazine advance mechanism

50 Mounted on the right hand end of the bridge 81 is a tunnel assembly 140 which comprises two channel-shaped members, an upper member 141 and a lower member 142, which are suitably riveted to each other to provide an open ended enclosure for slidably receiving the magazine 56. The upper member 141 is shown in Figs. 18 and 19, the complete tunnel assembly is shown in Figs. 22 and 6, and an enlarged view of certain of the working parts are shown in Fig. 20.

The tunnel assembly includes an index pinion assembly 143 which is rotatably mounted on a bracket 144 by means of a suitable bushing 149, as shown in Figs. 18 and 22. The index pinion assembly, as shown in Fig. 24 comprises a shaft 145, an index pinion 146 secured thereto at its lower end, a ratchet wheel 147 secured to the shaft above the index pinion, and guide disks 148 above and below the ratchet 147. As shown in Fig. 26, the magazine 56 is provided with a rack 150 which is engaged by the index pinion 146 so that the magazine can be advanced forwardly or backwardly by rotation of the shaft 145, or the whole index assembly 143. The slide selector knob 67 is connected to the upper end of the shaft 145, thereby permitting manual advance of the magazine.

Means are also provided to advance the magazine automatically, and such means include a reciprocating pawl

151 shown in Figs. 20 and 25 which engage the ratchet wheel **147**. The pawl is mounted on a lever **152**, pivoted at **153**, and a spring **154** is provided to bias the pawl **151** into operating position.

Pawl blocking means in the form of a slide **155** is provided to maintain the pawl **151** out of engagement with the ratchet wheel **147** when it is desired to advance the magazine manually, by the knob **67**. The slide **155** is provided with slots **156**, and is slidably mounted on the top surface of the upper member **141** by means of shoulder guides, or rivets **157**. A suitable spring **158** biases the slide **155** into its retracted and inoperative position.

The left end of the slide is bent over to provide a vertical surface **159** which is engaged by a cam **160** which is secured to a vertical function shaft **161**, this being the shaft on which the function knob **66** is mounted. Thus, when the knob **66** is rotated into the "manual" position, the cam **160** will actuate the slide **155** to disengage the pawl **151** from the ratchet **147**, so that the magazine can be shifted manually in either direction. Detent means are provided to locate the magazine so that each slide will register with the injector and ejector arms **124** and **126**. The detent means, shown in Figs. 20 and 26, include a detent lever **162** pivotally mounted on the under-surface of the upper member **141**, the forward end of which carries a wheel **163** which cooperates with the teeth of the index pinion **146**. A spring **164** biases the wheel **163** against the pinion **143**.

The lever **152** extends laterally to the right, beyond the pawl **151** and terminates in an end piece **165** provided with a slot **166**. A spring **167**, extending between the end piece **165** and a portion of the upper member **141**, biases the lever **152** and pawl **151** into retracted position. It can be pointed out that this position of the pawl **151** also permits the magazine to be advanced manually (if the injector arm **124** is retracted), but it will not permit reverse or rearward movement of the magazine. For rearward movement of the magazine, the pawl **151** must be displaced by means of the slide **155** and knob **66**. Furthermore, the detent means is not a lock; parts are so shaped that the magazine can be displaced by applying pressure directly to the magazine, instead of by operating the slide selector knob **67**.

Means are provided for displacing the lever **152** rearwardly to actuate the index pinion assembly **143**, and to advance the magazine. Such means include a bell crank **170** and a cam **174**. The bell crank, as shown in Figs. 20 and 22, is pivoted at **171** on the right side wall of tunnel assembly **140**. The upper end of the bell crank **170** is reduced and is received in the slot **166** of the lever **152**. A take-up spring **172**, is wrapped around a button **173** on the bell crank **170** for a purpose hereinafter described.

The cam **174**, shown in Figs. 13 and 17 is mounted on and secured to the cam shaft **118**. The transversely extending lever **175**, mounted on a pivot pin **176** extending rearwardly from the intermediate plate **83** carries at its left end a follower **177** which cooperates with the cam **174**. The lever **175** may comprise two spaced members so as to embrace, at the left end, the follower member **177**, and at the right end, the lower end of a link **178** which connects the lever **175** with the horizontally extending arm of the bell crank lever **170**. The connection between the link **178** and the bell crank lever **170** may be made by means of a shoulder pin **179** shown in Fig. 20, which is riveted to the link **178** and passes through a slot **180** in the horizontally extending portion of the bell crank lever **170**. The upper end of the spring **172** engages a lug **181** on the bell crank lever itself, and the other end engages the shoulder pin **179**, thus urging the link **178** upwardly and the lever **175** in the counter-clockwise direction so that the follower **177** is always biased into engagement with the cam **174**. Thus, the parts **174**, **175** and **178** are maintained under an operating

bias which is independent of the position of the lever **152** and the pawl **151**.

The retracted position of the parts **152**—**151** is determined by the vertical edge **182**. The throw of the pawl **151** can be regulated by adjustment of the nut **183** which carries the eccentric pin **184** by means of which the pawl **151** is pivotally mounted on the lever **152**.

The mechanism just described serves to convert the motion of the lever **175**, which is in a transverse vertical plane, to the forward and back motion, in a horizontal plane, of the pawl mechanism **151**—**152**. In operation, during each rotation of the cam shaft **118**, the pawl mechanism advances the index pinion **146**, and hence the magazine **56**, to the extent of one tooth, the tooth pitch corresponding to the distance between successive slide compartments in the magazine. The timing of the cam **174** with respect to the operation of the magazine advance mechanism, as pointed out above, is such that the magazine will be advanced during the time that the injector arm **126** is in its retracted position.

The cycling means

It has been pointed out that the cam shaft **116** is driven through a clutch assembly **93**, and that the clutch is maintained in engagement when the solenoid **110** is in its operated position. It has also been pointed out that the position of the solenoid armature **111** can be controlled either by the release button **63**, or by the microswitch **113**. The cycling means comprises the elements required

to bring the cam shaft **116** to a stop in either a predetermined angular position which represents the termination of a complete cycle, with the slide in projecting position, as shown in Fig. 9, or at the termination of a half cycle, in which the slide is in its magazine position, as shown in Fig. 10. As shown in Figs. 8-13, a follower arm **190** is mounted on the follower shaft **117**, and is provided at its left end with an operating follower **191** which is in the form of a bent end, disposed in substantially a horizontal plane. A cycling cam **192** is mounted on the cam shaft **116** for rotation therewith, and the surface of said cam, as shown in Fig. 28, comprises an operating portion **193**, and two stop portions, the latter comprising a full notch **194**, and a half notch **195**. The follower arm **190** is also provided with a secondary follower **196**, the operating follower **191** being offset forwardly therefrom and separated by a slot **197**, as shown in Fig. 12a. The slot **197** serves to accommodate the web portion **198** adjacent the half notch **195** so that, when the parts are in the Fig. 11 position, the followers **191** and **196** straddle the web portion **198** and permit the operating follower **191** to drop into the half notch **195**.

The follower shaft **117** is axially shiftable with respect to the plates **80** and **83** in which it is mounted, and a spring **199** pushes the shaft and follower rearwardly and at the same time biases the follower **191** against the cycling cam **192**. Thus, when the follower shaft **117** is permitted to move rearwardly of its Fig. 11 position, as shown in Fig. 12, the operating follower **191** will then ride on the periphery of the web portion **198**, with the result that the follower will drop only into the full notch **194**.

In other words, the combination of the axially shiftable follower arm **190** together with full notch **194** and half notch **195**, provides two different modes of operation. According to one mode of operation, the operating follower **191** will drop into either one of the notches **194**, **195**, thus providing two stop positions for the cam shaft, and according to the second mode of operation, it will drop only into the full notch **194**, thus providing only one stop position.

The purpose of the follower arm **190** is to provide a means for operating the microswitch **113**. As shown in Fig. 9, when the operating follower **191** is received within one of the notches, the right end of the follower arm **190** clears the plunger of the microswitch. However, when

the operating follower 191 engages the operating portion 193 of the cycling cam 192, as shown in Fig. 10, then the plunger of the microswitch is engaged by the follower arm 190 to operate the switch into closed circuit position, thus establishing and maintaining the circuit through the solenoid 110 and maintaining the clutch assembly 93 in engaged position.

To summarize the operation of the cycling means, after the clutch has been engaged, rotation of the cam shaft 116 will cause the cycling cam 192 to rock the follower arm 190 and close the solenoid circuit. The clutch will be automatically disengaged at the conclusion of a full cycle, when the operating follower 191 drops into the full notch 194, irrespective of the axial position of the follower shaft 117. In one position of the follower shaft 117, which position corresponds to the "manual" position of the function knob 66, the operating follower will also drop into the half notch 195, thus causing disengagement of the clutch about midway of the full cycle of operation. In other words, according to "manual" operation, the mechanism will operate through successive portions of a complete cycle, whereas in the other types of operation, it will operate only in complete cycles.

The cycling cam 192 forms a part of a cam assembly 200, shown in Fig. 27, the cam assembly being secured to the cam shaft 116 and driven by the main gear 120 as previously outlined. The cam assembly includes a hub 201 to which the cycling cam 192 and the magazine advance cam 174 are secured by rivets 202, the hub 201 being secured to the cam shaft by means of a pin 204. A shutter cam 203, to be described hereinafter, forms a part of the hub 201.

Thus, during full cycle operation, which starts with the slide in projecting position, as shown in Fig. 9, the cycle includes the successive steps of slide return, magazine advance, and slide feed. The slide return and slide feed comprise the return and feed strokes of the slide transporting mechanism previously described, which are driven from the cam shaft 116 by means of the crank pin 121 and link 122. The magazine advance is driven from the cam shaft by the cam 174 and its cooperating lever 175.

During half cycle operation, the first half cycle comprises only the step of slide return. The second half cycle comprises only the step of slide feed. The step of magazine advance is eliminated by virtue of the fact that the axial position of the follower shaft 117 is controlled by the angular position of the function shaft 161 in such a manner that when the follower shaft is displaced forwardly into its half cycle position, corresponding to "manual" operation, then the blocking cam 160 on the function shaft 161 actuates the pawl blocking means.

Cycling control

The cycling control includes the means for initiating each cycle of operation, together with the control mechanism associated with the function shaft 161 which controls the axial position of the follower shaft 117.

Three means are provided for initiating the cycle of operation. The first means comprises the release button 65 which operates through the rod 112 and the armature 111 in the manner previously described. The second means is the automatic cam assembly 205, and the third means is the remote control switch 230.

The automatic cam assembly 205 is rotatably mounted on cam shaft 116, as shown in Figs. 4, 11-13, and 27. The automatic cam assembly, as shown herein, comprises an integral member, one portion of which constitutes a worm wheel 206 which meshes with the continuously rotating worm 95 shown in Fig. 5. Thus, the automatic cam assembly is continuously driven from the motor 90, irrespective of whether or not the cam shaft 116 is being driven. However, the reduction gearing 98 and the worm drive cause the automatic cam assembly to be driven at a relatively slow rate of speed, such as one revolution per minute, for example.

The automatic cam assembly 205 also includes three sets of cam lobes, which may be referred to as the 180° set 207, the 120° set 208, and the 90° set 209, shown in Figs. 29-31. The lobe 210 is common to all three sets.

5 The secondary follower 196, on the axially displaceable follower arm 190, is adapted to be engaged by one or the other of the lobe sets 207, 208 or 209, as shown in Fig. 12, depending upon its axial position, or by neither, as shown in Fig. 11.

10 When the secondary follower 196 registers with lobe set 207, for example, then the follower arm 190 will be rocked every thirty seconds, thus closing the microswitch 113 and initiating a new cycle of operation every thirty seconds. This cycle of operation will be a full

15 cycle of operation, since in this position of the follower arm 190, the operating follower 191 will ride on the web portion 198. Thus, automatic operation is provided, since the cycle is initiated without depressing the release button 65.

20 Similarly, by shifting the position of the follower shaft 117 so that the follower arm 190 registers with the lobe set 208 or 209, cycling is automatically initiated at intervals of twenty seconds, or fifteen seconds, respectively. The intervals mentioned are illustrative only, since any

25 desired intervals may be obtained by suitable change in the reduction gearing 98, the worm and worm wheel 95-206, and the spacing of the lobe sets 207-209.

The automatic cam assembly 205 is secured in a pre-determined axial position by means of a suitable retaining ring 211. Although as shown as an integral member, it may comprise a composite member similar to the cam assembly 200.

To control the position of the follower shaft 117, a rock lever 214 is pivotally mounted on the side of lamp housing 215 by means of an eccentric pivot pin 213, of a construction similar to the eccentric pin 183-184. The lower end of rock lever 214 bears against the rear end of follower shaft 117, and the upper end bears against the rear end of a slide 216, also shown in Fig. 23. Any play may be taken up by adjustment of the eccentric pivot pin 213.

The slide 216 is provided with a slot 217 through which the function shaft 161 extends. Thus, the slide is guided in its forward and back motion by the function

45 shaft 161 and also by the edges of a notch 218 formed in the vertical plate 80, through which notch the slide extends. A rivet 219 projects downwardly from the front edge of the slide 216 and is engaged by a cam 220 secured to the lower edge of the function

50 shaft 161 so that rotation of the function shaft will cause rotation of the cam 220 and displacement of the slide 216. A suitable spring 221, shown in Fig. 23, urges the slide 216 rearwardly, and the rivet 219 into engagement with the cam 220. The spring 221 is stronger than

55 spring 199 on the follower shaft, and acts in opposition thereto; however, the position of the follower shaft is controlled by the spring 199 and by the position of the cam 220. The cam 220 is provided with a series of five surfaces 222, the lowest of which corresponds to "manual"

60 or half cycle operation and this, as pointed out previously, is the forwardmost position of the follower shaft 117, shown in Fig. 11. The second position corresponds to semi-automatic operation, in which the operating follower

65 191 rides on the web portion 198 to produce full cycle operation, but in which the secondary follower 196 is maintained out of registry with the automatic cam assembly 205. The third, fourth and fifth cam surfaces 222 correspond to "slow," "medium," and "fast," respectively, automatic operation.

70 In order to maintain the cam 220 in the desired position, in which proper registry is maintained between the follower arm 190 and the various lobe sets, or automatic cams, a series of holes 223 are formed in cam 220, one for each surface 222. A ball detent 224, shown in Fig.

75 7, cooperates with the holes 223. As shown in Fig. 7,

the ball detent is positioned in a suitable opening formed in the bridge member 81 and is maintained in that position by a suitable leaf spring 225.

The third means of providing automatic operation comprises a remote control switch 230 which is shunted around the microswitch 113, as shown in Fig. 43. The remote control switch 230 may be connected by means of a cord 231, plug 232, and socket, not shown, to leads 235 and 234 which shunt the microswitch 113. The remote control switch 230 is utilized in connection with semi-automatic operation. However, instead of initiating the cycle by manual depression of the release button 65, it is initiated by energization of the solenoid 110. As soon as the solenoid has been energized, the clutch will be engaged, and the cycling cam 192 will be rotated, thus closing the microswitch 113. Since all this takes place within a fraction of a second, all that is necessary to initiate the operation is a momentary closing of the switch 230, the microswitch 113 serving to maintain the clutch in engaged position for the duration of the cycle. The remote control switch 230 may either be a manually operated switch, or it may be a pulse actuated relay, the pulse being provided by a suitable signal recorded on the tape of a tape recorder, or provided by some other programming instrument.

The electrical operation is shown in Fig. 44 in which the reference numerals 236—237 designate the line leads. The switch 68 is a step switch connected to line lead 236, and comprises two terminals 238 and 239, and a contact member 240 having a substantially arcuate length so that it may make contact with terminal 238 alone or with both terminals 238, 239, or with neither. These three positions correspond to "blower," "lamp," and "off" positions, respectively, the "off" position being shown. A lead 241 is connected to the terminal 238, and the motor 90 is connected across leads 241, 237. A lead 242 is connected to terminal 239. A lamp 58 is connected across leads 242 and 237. The solenoid 110 is so connected across leads 242 and 237, and is in parallel circuit to the lamp 58. The microswitch 113 is connected in series with the solenoid 110 and remote control switch 230, when plugged in, is also in series with the solenoid 110 as indicated above. When the contact member 240 is thrown from "off" position into "blower" position, just the motor 90 is energized, but not the lamp circuit or the solenoid circuit. In this position, the mechanism can be caused to operate by depression of the release button 65, which provides manual engagement of the electrical assembly 93 but since the control circuit, including the solenoid 110 and the microswitch 113, is deenergized, the cycling means are inoperative. When the switch 68 is thrown into the lamp position, all three circuits are energized; the motor circuit, the lamp circuit, and the solenoid circuit, and the various types of operation above outlined are thereafter controlled by the position of the function knob 66.

The magazine

The slide magazine 56 is shown in Figs. 32—35. It comprises a partitioned tray which will be described with reference to the upright position in which it is shown in Figs. 32—34, this position corresponding to slide storage position. When the magazine is to be inserted into the tunnel 140, it is rotated toward one side through about 75°, as shown in Figs. 1, 6 and 9, this being the operating position.

The magazine comprises a front wall 245, which becomes the uppermost wall in operating position, a rear wall 246, end walls 247, and a bottom wall 248. A handle 249 may be provided on one of the end walls. The magazine is provided with a plurality of transverse partitions 250, thus providing a separate compartment for each slide. The rack 150 is formed on the front wall 245, so that when oriented in its operating position, it will cooperate with the index pinion 146, as shown

75

in Fig. 26. A longitudinal slot 251 is formed in the bottom 248 to accommodate the injector arm 124 in the manner shown in Figs. 8 and 9. A series of indicia 252, designating each compartment, is formed on the front wall 245 in a position in which the separate indicia may be exposed through an opening 253 in the closure 51, as shown in Fig. 2, thus indicating the particular slide which is positioned for projection. A second set of indicia 254 may be provided on the diagonally disposed back of the rack 150 so that the compartments may be identified when the magazine is oriented in storage position, as shown in Fig. 33.

Means are provided to maintain each slide centered in its respective compartment, such means comprises centering bosses 255 and 256, each of which provide 45° surfaces which are effective to center that edge of a slide which is adjacent the slot 251, so that the edge will be properly engaged by the concave edge 125 of the injector arm 124. The centering bosses 255 are formed at the intersection of the rear wall 246 and the partitions 250. Thus, when the magazine is in its operative position, the slide will rest on the 45° surfaces provided by the bosses 255, and be centered in the compartment, irrespective of variation of the thickness of the slide. In other words, some transparencies are mounted in glass, and are therefore thicker than those mounted in cardboard. The centering bosses 256 are formed at the intersection of the bottom wall 248 and the partitions 250, at a point adjacent to the front wall 245. The centering bosses 256 tend to center the edge which is adjacent slot 251, when the magazine is in its storage position. However, when in operative position, the centering bosses 256 are effective since there is a small gravitational component which urges the slide against the bosses 256. Thus, by virtue of this combination of bosses, the particular edge concerned is maintained in desired registry as the tray is rotated by the operator from its storage position up to its operative position. As shown in Fig. 34, the front and rear walls 245, 246, have a slight taper, and the centering bosses 255 are also tapered, with the result that a slide may be easily dropped into its compartment and its lower edge will become centered.

Means are provided to guide the magazine 256 within the tunnel 140, and to bear against the upper corner edge 257 so as to urge the rack 250 into engagement with the indexing pinion 146. Such means includes upper shoulders 258 and lower shoulders 259, shown in Figs. 6 and 8 which confine the magazine in the right hand portion of the tunnel. These shoulders, as shown in Figs. 18—20, may be formed by stamping the proper configuration in the upper and lower tunnel members 141 and 142. The slide members also are provided with guide tabs 260 at either end, forming a tapered surface to facilitate insertion of the magazine.

A roller 261, shown in Figs. 20 and 21 is carried on a spring 262 mounted on a post 263 which is riveted to the upper member 141. The spring 262 urges the roller against the edge 257 of the magazine 56 so as to take up any play in the rack and pinion 150, 146.

Projecting position

As shown in Figs. 4 and 8, an aperture 264 is formed in vertical plate 80. Above the aperture is a transverse upper plate 265, also shown in Fig. 9 which cooperates with the upper part of plate 80 to provide a channel 266. Disposed within the channel 266, is a generally arc-shaped guide strip 267 which forms a guide for the upper edge of a slide. The right hand portion of the guide strip terminates in a bracket 268, which partially encloses the wheel 261, the bracket being secured to the upper member 141 by means of screws 269.

Resilient means are provided which engage the slide to maintain the same in its projecting position, that is, in the light beam path, or optical axis.

Located immediately below the aperture 264 and some

what rearwardly of the plate 80 is a lower guide plate 270 having an arcuate edge. Guide wheels 271, 272 having concave edges, are suitably mounted between the plates 270 and 80, and are urged upwardly by suitable springs 273. The lower edge of a slide is engaged by the concave edges of the guide wheels 271, 272 and urged upwardly against the guide strip 267, thus holding a slide in a vertical plane when it is in projecting position, as shown in Fig. 9. The transverse position of the slide is determined by stop pins 275, against which the slide is urged by the injector arm 124.

A flanged disk 274 or pulley, is carried on the injector arm 126 and rides on the arcuate edge of the lower guide plate 270 to maintain the injector arm 126 and the disk 128 in the proper plane for engagement with the edge of the slide. Suitable nylon guides 276, secured to the lower tunnel member 142, as shown in Figs. 20 and 22, serve a similar guiding function for the injector arm 124, these nylon guides overlying a suitable slot 277 through which the arm 124 passes.

It will be observed in Fig. 10 that the normal position of the guide wheel 272 is somewhat higher than its position shown in Fig. 9. In the Fig. 10 position, the guide wheel 272 is engaged by the flanged disk 274 and depressed, as the injector arm 126 moves from the Fig. 10 position to the Fig. 9 position, and this occurs just prior to the time that the lower leading corner of the slide engages the guide wheel 272. In other words, the flanged disk 274 displaces the guide wheel 272 in such a manner that wear on the corner of the slide will be avoided, thus permitting the use of a fairly strong spring 273 without causing damage to the slide.

The shutter

As shown in Fig. 4, a shutter assembly 280 is located within and forms a part of the lens unit 55, the shutter assembly being located between two of the elements of the projecting lens 74, and being secured therein by suitable screws 279. The structure of the shutter assembly is shown in Figs. 36 to 39.

The shutter assembly comprises an apertured front plate 281, an apertured rear plate 282, an actuating ring 283, and a plurality of shutter blades 284. Shoulder rivets 285 are mounted in the rear plate 282 and provide means for securing the two plates to each other in spaced relationship. The actuating ring 283 is rotatably mounted with respect to the other elements, and this relationship is provided by means of an extruded edge 286, shown in Fig. 37, which is formed on the inner edge of the ring. The ring 283 is mounted immediately adjacent the rear plate 282, and the extruded edge 286 rides on the inner edge of the rear plate. Three or more extruded spacer knobs 287 project toward the front plate 281 and serve to avoid excess play of the parts in the axial direction.

A notch 288 is formed in the rear plate, and a bent-over lug 289 on the ring 283 extends rearwardly through the notch, the width of the notch serving to limit the rotational movement of the actuating ring 283. A spring 290 extends between the lug 289 and a lug 291 which is formed on the rear plate 282 so that the ring is biased in the clockwise direction, as viewed in Fig. 36, which corresponds to shutter closed position.

The ring 283 is provided with a plurality of extruded pivots 292, which serve as shiftable pivots for the shutter blades 284. The front plate 281 is provided with arcuate slots 293 to accommodate the pivots 292.

Each shutter blade 282, as shown in Fig. 39, is provided with a hole 294 which fits over one of the shiftable pivots 292, and is also provided with a slot 295 which fits over the spacer rivets 285. Thus, as the actuating ring 283 is shifted, each one of the shutter blades will be caused to move from shutter closed position into shutter open position, or vice versa. In the shutter open position, the blades are wholly retracted into the space between the ring 283 and front plate 281, and as pointed

out above, the extruded spacer knobs 287 maintain the required spacing.

The ring 283 is actuated by means of a sleeve 296, having a square hole, which is rotatably journaled in the rear plate 282, and projects rearwardly therefrom. Secured to the sleeve and rotating therewith, but located on the front side of the rear plate is a partial pinion 297 which meshes with rack teeth 298 formed on the ring 283. Thus, rotation of the sleeve causes operation of

10 the shutter.

The lens unit 55 is mounted in a generally tubular member or shell 300, as shown in Fig. 4 and is removably secured therein by a removable set screw 307. An edge portion of the shell 300 is provided with rack teeth 15 301, which mesh with a pinion 302 which is connected to the focusing knob 64. Thus, adjustment of the focusing knob shifts the shell 300 and the lens unit 55 back and forth.

To accommodate this focusing motion, a sliding connection is provided between the actuating sleeve 296 of 20 the shutter assembly, and the operating mechanism of the projector so that the shutter will be operated during each cycle of operation. This sliding connection includes a square shaft 303 which is rotatably mounted in 25 a plate 304 and projects forwardly therefrom as shown in Figs. 4 and 6. The plate 304 is located in front of the vertical plate 80. Secured to the square shaft 303 and rotating therewith is a partial pinion 305, as shown in Fig. 6, by means of which the square shaft 303 may 30 be rotated to open and close the shutter.

The shutter actuating means

The operating mechanism of the projector includes 35 shutter actuating means which is located in the mechanism assembly adjacent the cam assembly 200. Thus, the shutter is normally operated by the cycling means heretofore described, to cut off the light beam during the slide changing operation, that is, during the full cycle of operation of the mechanism. However, by 40 using an iris type shutter 280 located in the projecting lenses, as contrasted with the usual wipe blade located in the film plane, two important advantages are obtained: first, the light beam is cut off by a fade rather than a wipe, and secondly, the shutter can be used to regulate 45 the intensity of the light beam, that is, the light intensity of the projected picture.

To illustrate the latter point, a 500 watt lamp is required for normal light intensity at a screen distance of 20 feet, but is not suitable for a screen distance of six 50 or eight feet, or less. In the present device, a screen 306 is built into the removable cover 60 which is useful when showing slides to only two or three people under conditions where a full size screen is not available, as for instance, when the slide projector is used as a visual 55 aid for a salesman. With a standard type of lens, the screen 306 calls for a screen distance of 30 inches. Obviously, the light intensity would have to be cut down very substantially in order to obtain proper color values in the projected image.

60 To accomplish this result, regulation of light intensity, manually actuated means, including the shutter control lever 70 are provided for partially closing the shutter 280 even when in its "open" position. In other words, the manually actuated means are so related to the automatically actuated means that the size of the aperture formed by the shutter plates 284 can be controlled without interfering with the automatic shutter operation.

The shutter actuating means includes a rock shaft 310 65 journaled in vertical plate 80 and intermediate vertical plate 83, as shown in Figs. 15 and 16. The rock shaft includes an enlarged hub portion 311 and a reduced hub portion 313. A sector 312 is suitably staked to the rear end surface of the hub portion 311. A double arm follower 314 is rotatably mounted on the reduced hub portion 313. A nylon follower disk 315 is mounted be-

tween the two arms of follower 314 and is engaged by the shutter cam 203, as illustrated in Fig. 15, the shutter cam forming a part of the cycling cam assembly 200 as shown in Fig. 27. A pin 317 extends through the reduced hub portion 313 at a point between the two arms of the follower 314 and is adapted to engage the rivet 316. Thus the pin and rivet arrangement permits clockwise movement of the sector 312 with respect to the follower as viewed in Fig. 15, but it limits or defines the angular position of the two in the opposite direction. A relatively strong spring 318 engages the parts 312 and 314 to urge them into their limiting relative position. The arrangement is such that when the follower 314 is actuated by the shutter cam 203, the whole assembly will be rocked in the counterclockwise direction as viewed in Fig. 15, since the spring 318 tends to maintain the elements 312 and 314 in the relationship shown in Fig. 15. A secondary spring 319 tends to rock the whole assembly in the clockwise direction, so that the follower disk 315 will engage the shutter cam 203.

The sector 312 meshes with the partial pinion 305, as shown in Fig. 6, to rock the square shaft 303 once during each revolution of the cam assembly 200. The connection of the parts is such that when the follower is in its actuated or Fig. 15 position, the shutter assembly 280 is open and this position of the parts corresponds to the projecting position of the slide. At other times, the shutter is closed, so that light will not be projected on the screen when the slide is being ejected and a new slide injected. In other words, the timing of the shutter actuating cam 203 is such that the shutter is closed during practically the whole of the full cycle of operation; it is open only during the interval between successive cycles.

The arrangement described above in connection with Fig. 16 permits the shutter to be partially closed to regulate light intensity, even when the parts are in the Fig. 15 or actuated position, since it permits clockwise movement of the sector 312 beyond the position shown.

The partial closing of the shutter is effected by the manual actuating means referred to above, which includes the shutter control lever 70 which is pivotally mounted on the plate 304 by the pivot rivet 321, shown in Figs. 6, 40 and 41. The plate 304 is provided with an arcuate slot 322, and the shutter control lever 70 carries a flanged rivet 323 which extends rearwardly into the slot and engages the edges thereof to provide a frictional engagement. Thus, the lever 70 may be maintained in any desired position, against the bias of a relatively strong spring 318, as will be pointed out. The plate 304 is deformed forwardly as indicated at 325, in Figs. 40 and 41, at a point adjacent the slot 322, so that the rivet will not project into the space behind plate 304 to interfere with the functioning of the stereo slot 71.

The shutter control lever 70 is provided with a downwardly projecting lug 324 which engages the sector 312 to rotate the latter in the clockwise direction, as viewed in Fig. 15, and as above described, against the bias of spring 318. Thus, the square shaft 303 may be maintained in a position corresponding to a partial closing of the shutter without in any manner interfering with the rocking motion imparted to the square shaft 303 by the shutter cam 203.

When the shutter is in its closed position, the sector 312 will be to the right of its Fig. 15 position, and clear of the lug 324. Since the square shaft 303 and the rock shaft assembly 310, 312, 314, are biased into the shutter closed position by the spring 319 and since the shutter plates themselves are biased into closed position by the spring 290, the square shaft 303 and the sleeve 296, when the shutter is closed, will always be in the identical angular alignment. Thus, it is possible to remove the lens unit 55 and replace it, providing the shutter is closed, without specially manipulating the respective parts to provide the proper angular alignment. As an exam-

ple, there may be situations in which it may be desired to substitute the lens unit 55 and this is done by releasing the set screw 307 (Fig. 4) and removing the lens unit 55 from the shell 300.

The stereo slot and pointer

Figs. 40 and 41 show a separate plate assembly 330 having flanges 331 by means of which it may be secured, as by riveting, to the main vertical plate 80 and the horizontal bridge member 81, at a point overlying the aperture 264 in plate 80. This plate assembly comprises the previously mentioned plate 304 and a second plate 332, both of which are apertured, as designated by the reference numeral 264 which applies to the aligned apertures in all three of the plate elements 80, 304 and 332.

The plates 304 and 332 are secured to each other by suitable spacers 333, and thus define the previously defined stereo slot 71. There are situations in which the operator may wish to project a picture which was taken

on a stereo slide, and hence will not be accommodated within the magazine 56, since a stereo slide is a double slide. To accommodate this situation, a separate projecting position is provided for such slides, in the form of the stereo slot 71, which permits one of the transparencies of the stereo slide to be interposed in the optical axis or light beam path of the projector, this being, of course, a manual operation. The stereo slide is maintained in its projecting position by means of a lower guide strip 334, having a generally V-shaped cross section, and by resilient means in the form of a guide wheel 335 mounted on a spring 336. The guide strip 334 engages the lower edge of the stereo slide, and the guide wheel 335 engages the upper edge, so that the slide is properly centered within the stereo slot 71. The spring 336 is wrapped around a suitable post 337 mounted in the second plate 332. An upper guide strip 338 may be provided to facilitate the insertion of the stereo slide within the slot 71.

The separate plate assembly 330 also includes a pointer which, since it is located approximately in the film plane of the automatically projected slides, will be projected on the screen, and the position of this pointer may be regulated by the operator to point to any portion of the projected picture that he desires. The pointer comprises a pantograph type of linkage comprising main links 340 and 341 and pivot links 342 and 343. The main link 340 constitutes the pointer, its outer end being suitably shaped, and the main link 341 comprises the manually actuated member which terminates in the pointer knob 69. The pivot links 342 and 343 are secured by a suitable pivot rivet 344 to the second plate 332, and are connected at their lower ends to the main links in the manner shown in Fig. 42. Thus, the position of the pointer may be suitably regulated by manipulation of the pointer knob 69.

Since the image on the slide is inverted, and since the pantograph arrangement shown is a motion inverting device, it will be seen that the motion imparted by the operator to the pointer knob 69 will be identical, as to direction, to the motion of the projected image of the pointer. Thus, the operator can be directly guided, in his manipulation of the knob 69, by the position of the projected pointer image on the screen without having to make mental allowance for image inversion.

Lamp mounting means

Adjustable lamp mounting means are provided so that the filament 350 of any particular lamp 58 may be adjusted with respect to the focus of the optical system, and in particular, with respect to the focus of the concave reflecting mirror 72 to provide an intertwining of the grid type filament and its reflected image. Such adjustable mounting means includes the lamp socket 345 and a mounting plate 346, as shown in Fig. 4. The mounting plate is secured to the bottom wall 349 of the lamp

housing 215 by means of three screws 347a, 347b, 347c, arranged as shown in Fig. 2. The adjustable mounting plate 346 is in the form of a right triangle, and is provided with tapped holes to receive the three screws 347. Compression springs 348 surround the screws and are disposed between the plate 346 and the bottom wall 349 in each instance.

Thus, it will be seen that the screws 347 and springs 348 provide a three point adjustable mounting for the plate 346, thus permitting the plane of the plate to be slightly inclined in any direction so as to align the filament 350 with the focus of the reflector 72. In particular, the right triangular arrangement of the three screws permits screw 347a to be used for a horizontal transverse adjustment, and screw 347b to be used for a horizontal longitudinal adjustment. Whereas all three screws contribute to the vertical adjustment, screw 347c could be considered as controlling since it is much closer to the vertical line through the focus of the reflector 72 than are the other two screws. Thus, means are provided to adjust the position of the lamp filament with great accuracy.

Operation

To summarize the operation which has been described in detail in connection with the description of the several parts and sub-assemblies, the type of operation is controlled by the function knob 66, which provides three different types of operation; manual, semi-automatic, and automatic. Since the operating cycle starts and terminates when the slide is in its projecting position, it is necessary to load the projector when the mechanism is in the half cycle, or mid-cycle position, which corresponds to the magazine position of the slide.

The mechanism is brought into this position by rotating the function knob 66 into its "manual" position. Then the switch 68 is turned to the "lamp" position, and the release button is depressed to cause the mechanism to operate through the first half of the cycle and come to rest in a position in which the injector arm 124 is retracted. Then the magazine 56 can be inserted into the tunnel.

If it is desired to show any particular slide in the magazine, the magazine is pushed through the tunnel until the corresponding indicia 252 is exposed to view through the opening 253. Then the release button 65 is depressed; the slide is projected; the release button is again depressed, and the slide is returned to the magazine. Then another slide is selected. When the knob is in this "manual" position, the magazine position may be changed in either direction, either by pushing the magazine, against the action of the index pinion 146 and detent 163, or by operating the slide selector knob 67.

For semi-automatic operation, where it is desired to show all the slides in a magazine in consecutive order, the magazine is positioned so that the No. 1 slide indicia is exposed through opening 253. Then the function knob 66 is turned to its "semi-automatic" position. Since the web 198 blocks axial movement of the operating follower 191, and the follower shaft 117, it is necessary to depress the release button 65 to initiate operation. The No. 1 slide is then moved into projecting position and will remain there until the release button 65 is again depressed, at which time a full cycle of operation takes place and the No. 2 slide is moved into projecting position. The same results can be obtained by depressing the remote control switch 230.

For automatic operation, the function knob 66 has three positions; slow, medium and fast, and it may be moved into any one of these three positions to provide fully automatic operation which requires no attention from the operator until the 36th slide is being exposed, at which time the function knob should be turned back to the manual position so that the magazine can be withdrawn. However, if the operator fails to do this, and the magazine automatically is advanced beyond the

last position, the injector arm 124 will engage the sloping end wall 351 of the magazine 56, and cam the magazine forwardly as the injector arm 124 advances until it is obstructed by the handle 249. Thereafter, the lost motion mechanism takes up the motion of the rock shaft 118, and the mechanism will continue to cycle until the operator turns it off.

Different intervals of projection can be provided, depending upon the particular automatic position into which the function knob is rotated.

The operation of the machine automatically closes the shutter during the slide changing operation, and the light intensity can be cut down by manipulating the shutter control lever 70.

15 The tunnel assembly 140 provides means for locating the magazine 56, and in particular, the slides contained therein, in a position transversely displaced from the optical axis. One important feature of the present invention resides in the nature of the slide displacing means 20 provided for displacing or translating a slide from magazine position to projecting position, and vice versa. This displacement is effected by a rotating mechanism, as contrasted with a translating mechanism, and, therefore, provides a much more compact mechanism assembly.

25 The slides are maintained in centered position in their respective compartments by the two sets of centering bosses 255 and 256 which are oriented substantially perpendicular to each other. However, in order to obtain maximum effectiveness of these bosses, the magazine is 30 maintained in an angularly displaced position, that is, it is tilted approximately 15° away from the vertical. Therefore, a small amount of rotation must be imparted to the slide during transaction from magazine position to projecting position and this rotation is provided by the 35 arc-shaped guide strip 267, and its cooperating parts.

It will be observed that the radius of the guide strip 267 is much greater, say three or four times greater, than the radius of the arcuate portion 124A of the injector arm 124, with the correlative result that slide is 40 rotated through approximately 15° while the injector arm 124 is being rotated through substantially 60°. This results in a certain amount of relative motion between the concave edge 125 of the injector arm 124, and the corresponding edge of the slide, as well as a certain 45 amount of relative motion between the disk 128 of the ejector arm 126 and its corresponding edge of the slide. However, by providing an arc-shaped slide path (guide strip 267) the extent of this relative motion is somewhat reduced, as contrasted with a straight slide path.

50 In particular, it will be observed that by providing for the injector and ejector arms 124 and 126 a radius much less than the radius of the slide path, a much more compact mechanism is provided than if the radii of these arms were identical to the slide path radius. Thus, compactness has been achieved not only by providing rotating 55 mechanism as contrasted with translating mechanism, but also by reducing the radii of the slide displacing elements to only a fraction of the slide path radius.

The results outlined above are implemented by the 60 provision of a separate pivot point for the ejector arm 126 and a link connection with the injector arm 124, rather than by the use of a common pivot point and a rigid connection.

As previously described in detail, a considerable 65 amount of lost motion is provided between the rock shaft 118 and the slide in order to accommodate magazine advance and clutch operation, some of this lost motion being provided by the spacing between the slide engaging elements 125 and 128, and some being provided 70 by the overthrow mechanism 130-137. As a result of this lost motion providing means, it is possible to actuate the rock shaft by the harmonic motion provided by a crank and connecting rod, 121, 122, as contrasted with a cam provided with dwell surfaces. The advantage of the crank arrangement over the cam is that the driven

parts are positively connected at all times to the driving parts, and this is particularly advantageous in motor driven mechanism where the load is substantial.

By the use of a solenoid actuated disk clutch, more positive and rapid operation is obtained than by the use of other types of clutching action. Furthermore, the solenoid permits electrical control rather than mechanical control, which reduces the load on the cams, and which permits the utilization of several alternative types of control means, all operating through one cycling means. Furthermore, the particular arrangement herein disclosed combines mechanical and electrical control elements in such a manner that holding relays are eliminated, and only the single control switch 113 is required, except under remote control conditions.

Although only a preferred embodiment of our invention has been shown and described herein, it will be understood that various modifications and changes may be made in the construction shown without departing from the spirit of our invention as pointed out in the appended claims.

We claim:

1. In an automatic slide projector having drive means and a drive shaft adapted to be driven from said drive means, the combination of cycling means and control means therefor, said cycling and control means comprising electrically controlled clutch means interposed between said drive means and said drive shaft to control the rotation of the latter, a cycle terminating cam mounted on said drive shaft and rotating therewith, control cam means rotatably mounted on said drive shaft for initiating the cycle of operation, said control cam means being continuously driven by said drive means, a control switch electrically connected to said clutch means for controlling the operation of said clutch means, and a common follower mounted for cooperation both with said cycle terminating cam and with said control cam means for operating said switch, slide displacing means, magazine advance means, means for establishing a driving connection between said drive shaft and slide displacing means, a magazine advance cam mounted on said drive shaft and rotating therewith for actuating said magazine advance means, means for axially displacing said common follower to cause the same to move out of registry with said control cam means, and means actuated by said follower displacing means for rendering said magazine advance means inoperative.

2. In an automatic slide projector having drive means and a drive shaft adapted to be driven from said drive means, the combination of cycling means and control means therefor, said cycling and control means comprising electrically controlled clutch means interposed between said drive means and said drive shaft to control the rotation of the latter, a cycle terminating cam mounted on said drive shaft and rotating therewith, control cam means rotatably mounted on said drive shaft for initiating the cycle of operation, said control cam means being continuously driven by said drive means, a control switch electrically connected to said clutch means for controlling the operation of said clutch means, and a common follower mounted for cooperation both with said cycle terminating cam and with said control cam means for operating said switch, slide displacing means, magazine advance means, means providing a driving connection between said drive shaft and slide displacing means, a magazine advance cam on said drive shaft and rotating therewith, manually operated means for initiating the cycle of operation, manually operated means for operating said magazine advance means, means for axially displacing said common follower to cause the same to move out of registry with said control cam means, means providing a driving connection between said magazine advance cam and said magazine advance means, and means actuated by said follower displacing means for rendering said second-mentioned driving connection providing means inoperative

whereby operation of said follower displacing means will provide either for automatic cycle initiation and automatic magazine advance, or for manual operation without automatic magazine advance.

5 3. In a slide projector, the combination of slide displacing means, magazine advance means, a drive shaft, electrically controlled means for imparting rotation to said drive shaft cycling means for terminating the cycle of operation of said drive shaft, said cycling means including a control switch for controlling the operation of said rotation imparting means and a magazine advance cam mounted on said drive shaft, first means providing a driving connection between said drive shaft and said slide displacing means, second means for establishing a driving connection between said magazine advance cam and said magazine advance means, manually operated means for initiating the operation of said cycling means, said cycling means also including a cycling cam having a full notch and a half notch, and a follower engaging said cycling cam for operating said control switch, and means for axially shifting said follower into either a first position in which it cooperates only with said full notch, or into a second position in which it cooperates with both said full notch and said half notch to interrupt the cycle of operation at an intermediate point, and means controlled by the movement of said follower shifting means into said second position for rendering said second driving connection means inoperative so as to provide either for semi-automatic operation when in said first position or manual operation when in said second position.

20 4. A slide projector of the magazine type and which embodies reciprocating slide transporting means for moving a slide between magazine position and projecting position, and vice versa, characterized by the combination of a rotatable drive shaft, a motor for said drive shaft, electrically controlled clutch means disposed between said motor and said drive shaft, mechanism connecting said drive shaft with said slide transporting means to impart reciprocating movement thereto, cycling means to cause said drive shaft to come to a stop in a predetermined angular position which corresponds to the projecting position of said slide, and automatic control means to initiate operation of said cycling means, said cycling means comprising a switch electrically connected to said clutch means which, when in closed position, causes rotation of said drive shaft, a cycling cam mounted on said drive shaft, and a follower interposed between said cycling cam and said switch, said cycling cam having an operating portion which cooperates with said follower to maintain said switch in closed position after the rotation of said cycling cam has been initiated, and having switch controlling means cooperating with said follower to open said switch when said drive shaft arrives at said predetermined angular position, the angular position of said switch controlling means with respect to said follower corresponding to said predetermined angular position of said drive shaft, said automatic control means including a continuously rotating control cam driven by said motor and located adjacent said cycling cam, and said follower being shiftably mounted for movement between two positions in a direction perpendicular to the direction of its movement when displaced by said cycling cam and having an operating portion and a secondary portion both of which, when in one position, engage said cycling cam and said control cam respectively, whereby the cooperation of said control cam and said follower will dominate the cooperation of said cycling cam and said follower to provide automatic operation for said slide projector, and means for shifting said follower into a second position to disengage said secondary portion from said control cam so that the cooperation between said cycling cam and said operating portion of said follower will control the operation of said switch, and additional means for initiating operation of said cycling means when said follower is

in said second position to provide semiautomatic operation for said slide projector.

5. In a slide projector as claimed in claim 4 in which said additional means for initiating operation of said cycling means includes a second switch connected in shunt relationship to said first mentioned switch.

6. A slide projector as claimed in claim 4 in which said switch includes a biased open control plunger, and in which said switch controlling means of said cam comprises a depressed portion, whereby said cycling cam and said control cam may be both located on the same side of said follower.

7. A slide projector of the magazine type and which embodies reciprocating slide transporting means for moving a slide between magazine position and projecting position, and vice versa, characterized by the combination of a rotatable drive shaft, electrically controlled means for imparting rotation to said drive shaft, mechanism connecting said drive shaft with said slide transporting means to impart reciprocating movement thereto, cycling means to cause said drive shaft to come to a stop in a predetermined angular position which corresponds to the projecting position of said slide, and control means to initiate operation of said cycling means, said cycling means comprising a switch electrically connected to said rotation imparting means which, when in closed position, causes rotation of said drive shaft, a cycling cam mounted on said drive shaft, and a shiftable follower mounted for shifting movement and interposed between said cycling cam and said switch, said cycling cam having an operating portion which cooperates with said follower to maintain said switch in closed position after the rotation of said cycling cam has been initiated, a first switch controlling means cooperating with said follower to open said switch when said drive shaft arrives at said predetermined angular position, the angular position of said switch controlling means with respect to said follower corresponding to said predetermined angular position of said drive shaft, a second switch controlling means which, with respect to said first switch controlling means, is narrower in the direction of the shifting movement of said follower, said operating portion being continuous adjacent said narrow portion so that when said follower is shifted into a position in which it registers only with said first switch controlling means, it will be engaged by said operating portion at a point adjacent said narrower second switch controlling means, said follower being adapted either to be engaged only by said first switch controlling means when it is desired to cause said drive shaft to come to a stop only at the end of the complete operating cycle, or to be engaged by both of said switch controlling means when it is desired to have said drive shaft come to a stop both at an intermediate position of said cycle and at the end of said cycle, and means for shifting the relative position of said follower and said cycling cam so that said follower will be engaged either by only said first switch controlling means, or by both of said switch controlling means.

8. A slide projector as claimed in claim 7 in which said rotation imparting means includes a continuously operating motor, and clutch means disposed between said motor and said drive shaft, and in which said cycling means includes electromagnetically operated actuating means for said clutch means controlled by said switch in order that said drive shaft may be rotated when said switch is maintained in closed position, and in which said control means includes manually operated actuating means for said clutch means to initiate rotation of said drive shaft.

9. In an automatic slide projector embodying mechanism for performing the functions of shutter operation, slide transporting which includes a return stroke and a feed stroke, and magazine advance, the combination of a rotatable drive shaft, a motor for driving said drive shaft, electrically controlled clutch means disposed between said motor and said drive shaft, cycling means including a

switch electrically connected to said clutch means which, when in closed position, causes rotation of said drive shaft, and a cam assembly, said cam assembly comprising said drive shaft, a cycle terminating cam, a shutter cam, a magazine advance cam, and a crank mounted on said shaft, means providing a driving connection between said crank and said slide transporting mechanism, means connecting said shutter cam to the shutter operating mechanism, means connecting said magazine advance cam to the magazine advance mechanism, automatic control means to initiate operation of said cycling means, a control cam rotatably mounted on said shaft and continuously driven by said motor, said cycling means and said control means including a common follower arm mounted for cooperation with said cams for operating said switch, and shiftable between two positions, and having an operating portion which, when said follower is in either position, engages said cycle terminating cam so that said follower arm will be displaced in one direction to open said switch, and having a secondary portion which, when said follower arm is in one position, engages said control cam so that said follower arm will be displaced in the other direction to close said switch whereby the cooperation of said follower arm and both of said cams will provide automatic operation for said slide projector, means for shifting said follower into a second position to disengage said secondary portion from said control cam so that the cooperation between said cycle terminating cam and said operating portion will terminate the cycle of operation when once initiated, and additional means for initiating operation of said cycling means when said follower arm is in said second position to provide semi-automatic operation for said slide projector.

10. The combination as claimed in claim 9 in which said control cam means includes a plurality of cams secured to each other in axially spaced relationship, and means for controlling the axial position of said follower so as to provide selective cooperation between said secondary portion and one of the other of said control cam elements whereby the interval between successive operations of said follower may be changed.

11. The combination claimed in claim 9 in which the relationship between the elements of said cycling cam assembly is such that the cycle of operation includes the successive steps of shutter closing, return stroke, magazine advance, feed stroke, and shutter opening, the timing of such elements being such that said return stroke and said feed stroke occur during the more efficient portions of the cycle of operation of said crank means, and the magazine advance and shutter operation occur during the less efficient portions which correspond to the end portions of said crank movement, said driving connection providing means including overthrow mechanism to take up the less efficient portions of said crank movement.

12. In an automatic slide projector the combination of slide transporting mechanism, a rotatable drive shaft, a motor for driving said drive shaft, electrically controlled clutch means disposed between said motor and said drive shaft, cycling means including a switch electrically connected to said clutch means which, when in closed position, causes rotation of said drive shaft, and a cam assembly, said cam assembly comprising said drive shaft, and a cycle terminating cam and a crank mounted on said shaft, automatic control means to initiate operation of said cycling means comprising a control cam rotatably mounted on said shaft and continuously driven by said motor, said cycling means and said control means including a common follower arm pivotally mounted for cooperation with said cams for operation of said switch, and shiftable between two positions, and having an operating portion which, when said follower arm is in either position, engages said cycle terminating cam so that said follower arm will be rocked in one direction to open said switch, and having a secondary portion which, when said follower arm is in one position, engages said control cam

so that said follower arm will be rocked in the other direction to close said switch whereby the cooperation of said follower arm and both of said cams will provide automatic operation for said slide projector, means for axially shifting said follower arm into a second position to disengage said secondary portion from said control cam means so that the cooperation between said cycle terminating cam and said operating portion will terminate the cycle of operation when once initiated, and additional means for initiating operation of said cycling means when said follower arm is in said second position to provide semi-automatic operation for said slide projector, said slide transporting mechanism including a rock shaft, an injector arm mounted on said rock shaft and oscillating therewith, and a link connecting said crank and said rock shaft, whereby the cyclical operation of said drive shaft may be imparted to said injector arm.

13. An automatic slide projector as claimed in claim 12 in which said slide transporting mechanism is operative in a return stroke and a feed stroke, said injector arm being operative during said feed stroke to displace a slide into a projecting position, and which includes a pivotally mounted ejector arm operative during said return stroke, means providing a driving connection between said ejector arm and said injector arm, stop means for said slide transporting mechanism to limit the extent of said feed and return strokes, and overthrow means disposed between said rock shaft and said injector arm to take up the end portions of the oscillating movement of said rock shaft.
